UNITED STATES PATENT OFFICE.

WILLIAM WHARTON, JR., OF PHILADELPHIA, PENNSYLVANIA, ASSIGNOR
TO WILLIAM WHARTON, JR., & CO., (LIMITED,) OF SAME PLACE.

RAILWAY-CROSSING.

SPECIFICATION forming part of Letters Patent No. 359,116, dated March 8, 1887.

Application filed November 9, 1886. Serial No. 218,384. (No model.)

To all whom it may concern:

Be it known that I, WILLIAM WHARTON, Jr., a citizen of the United States, residing in Philadelphia, Pennsylvania, have invented
5 certain Improvements in Railroad-Crossings, of which the following is a specification.

The object of my invention is to construct a railroad-crossing of four rails, thus dispensing with the usual heavy crossing-castings now used extensively in street-railways, and with the complicated steam-railway crossing formed of a number of small pieces of rails.

In the accompanying drawings, Figure 1 is a perspective view of my improved railway-crossing. Fig. 2 is a section on the line 1, 2, Fig. 1. Fig. 3 is a section on the line 3, 4, Fig. 1; and Figs. 4 and 5 are perspective views of two rails detached from each other.

15 A A' are the rails of one track, B B' the rails of another track crossing at an angle thereto. In the drawings I have shown the tracks as crossing at right angles; but I do not limit my invention to right-angled crossings.

20 The rails illustrated in the drawings have very high webs, intended more especially for street-railways, and are adapted to be fastened directly to the cross-ties by means of chairs, thus dispensing with the usual wooden stringers.

25 The rails A A' are transversely slotted on their under sides at *a a* to about one-half their height, portions of the bases and webs being cut away. The rails B B' are transversely slotted at their upper sides at *b b*, portions of the heads and webs being cut away. The rails A A' and B B' are then fitted together or

“halved,” the upper portion of the web of the rails A A' fitting into the slots *b* and the lower portion of the web of the rails B B' fitting into 40 the slots *a* in the rails A A', thus forming a neat and strong halved joint. Each of the rails is grooved at *c*, adjacent to the joint, to allow for the passage of the flanges of the car-wheels.

45 Under each of the halved joints I prefer to place a base-plate, D, as shown in Fig. 1. This plate has tapering undercut ribs *d* on the upper surface, between which and the dovetailed bases of the rails tapered wedges are 50 inserted for securing the rails firmly in place and to the base-plates D.

The rails may be secured at the joints by angle fish-plates or elbow-pieces; but I prefer in all cases to use the base-plate D, whether 55 the angle fish-plates or elbow-pieces are used or not. By this construction I am enabled to form a crossing of ordinary girder or web rails without interfering with the continuity of the tracks, and at the same time a very strong, 60 neat, and simple crossing is produced, which can be readily put down and easily repaired.

I claim as my invention—

The railway-girder crossing composed of 65 four rails halved together at the joints, substantially as and for the purpose described.

In testimony whereof I have signed my name to this specification in the presence of two subscribing witnesses.

WILLIAM WHARTON, JR.
